VACUUM CLEANER

Ernst Fredrik Georg Fredlund, Stockholm,
Sweden, assignor to Electrolux Corporation,
Dover, Del., a corporation of Delaware

Application December 18, 1934, Serial No. 757,993
In Germany December 21, 1933

6 Claims. (Cl. 230—232)

My invention relates to vacuum cleaners and more particularly to means for reducing the noise emitted from a vacuum cleaner due to the operation of the motor-fan unit.

According to the invention this reduction in noise is mainly effected by constructing and arranging the outer and inner parts of the cleaner, especially those parts placed behind the fan counted in the direction of flow of air, in such manner that at least one of the air channels defined by said parts is equivalent to an air cylinder the diameter of which is preferably less than its length and at the most less than twice its length and which begins and ends with sudden changes in area. The arranging of the air passage in this manner causes sudden contractions and expansions of the air passing therethrough which has the effect of reducing the noise of the motor fan unit which is emitted from the cleaner.

Further objects and advantages of my invention will be apparent from the following description considered in connection with the following drawing which forms a part of this specification and of which:

Fig. 1 is a diagrammatic view illustrating the principle of my invention; and

Fig. 2 is a cross-sectional view of my invention embodied in a preferred form of vacuum cleaner.

In Fig. 1 there is shown diagrammatically an air passage comprising sections *a*, *b* and *c*. The diameters of these sections are represented by *x*, *y* and *z*, respectively, and it will be noted that adjacent sections are of different diameter and that the change in diameter between adjacent sections is abrupt. The length of the respective sections are represented by *o*, *p* and *q* and it will be noted that in each case the length is greater than the diameter of the respective section.

When air is passed through a passage of the type shown diagrammatically in Fig. 1, sound waves which may be present in the air at the entrance end of the passage are reduced to a great extent by the time the air leaves the passage. This is due to the sudden compression and expansion of the air as it passes from a section of one diameter to a section having a different diameter.

In Fig. 2 there is shown a vacuum cleaner so constructed that the passage for the flow of air from the fan to the outlet contains portions or sections having free flow areas arranged in accordance with the principle illustrated in Fig. 1. Reference character 10 designates a preferably

cylindrical casing. To one end of casing 10 a cap 11 may be secured in any suitable manner, as by spring clips 12. Cap 11 is formed with a centrally threaded aperture into which a coupling member 13 may be screwed. Coupling 13 has a central aperture adapted to receive a flexible hose 14 which may be connected to any suitable suction nozzle or other cleaning implement. A ring 15 is adapted to be clamped between cap 11 and the end of casing 10 and serves to support 10 the open end of a dust bag 16.

The other end of casing 10 is provided with a ring 17 to which may be secured, in any suitable manner, a motor supporting ring 18. Ring 18 is provided with a plurality of lugs 19 which carry 15 pins 20. These pins support the inner ends of coil springs 21, the other ends of which are secured to a motor housing 22. Housing 22 is provided with a forward bearing shield 23 and a rear bearing shield 24. These shields are formed 20 with openings 25 and 26, respectively, which communicate with air passages 27 extending through the field of the electric motor. An armature 28 is rotatably supported in the bearing shields and the forward end of armature shaft 29 supports 25 fan rotors 30 and 31.

An inner fan housing 32 is formed with a cylindrical portion surrounding rotor 31 and with a forward wall having a central opening 33 therethrough. An outer fan housing 34 surrounds 30 rotor 30 and has a forward wall with a central opening 35 therethrough. The rear ends of both the fan housings are formed with outwardly extending flanges which are clamped with a packing ring between rings 17 and 18, whereby the 35 fan housings are secured in place. Forward bearing shield 23 supports a circular plate 36 disposed immediately behind rotor 31. Plate 36 is formed with a cylindrical flange portion 37 which is concentric with the cylindrical portion 40 of inner fan housing 32 and forms an air flow channel 38 therebetween. Radially extending guide vanes 39 may be supported by forward bearing shield 23 and serve to reduce the rotational movement of air passing from the rotors 45 toward the motor. A sealing ring 40 carried by the forward bearing shield 23 serves to cause all of the air discharged from the fan to pass through the air passages 27 in the motor in order to obtain maximum cooling of the latter. 50

A hood member 41 surrounds the rear end of the motor and is supported from motor ring 18 by means of bolts 42. Hood member 41 has a cylindrical portion 43 which is spaced inwardly from the cylindrical portion of an end cap 44 so 55

as to form an annular channel 45 therebetween. A plurality of openings 46 are formed in the cylindrical portion 43.

Cap member 44 is formed with an end wall 41 provided with a centrally located outlet opening 48. Inclined vanes 49 extend across the outlet opening and the more central vanes are formed integral with a sleeve 50. A bolt 51 extends within sleeve 50 and has threaded engagement with the end of hood member 41, thus serving to hold the cap 44 in place. A filter member 52 may be located between the end of hood 41 and the outlet 48.

A circular disc 53 is disposed within cap member 44 adjacent to outlet 48 and may be supported by vanes 54, which also serve to reduce whirling of air. Plate 53 and the end 47 of cap 44 form between them a discharge channel 55 leading to the outlet 48. As is shown in Fig. 2, the end wall 41 is formed as a hyperbolic surface, whereby the cross-sectional area of discharge channel 55 is constant throughout its length.

It will thus be seen that the passage through which the air must pass from the rear rotor 31 to the outlet 48 comprises a plurality of sections. The first is the air flow channel 38 between the inner fan housing 32 and cylindrical flange 31. The second is made up of the air passages 27 through the motor. The third is the annular channel 45 between hood 41 and cap 44. The fourth is the discharge channel 55 between plate 53 and end wall 41. The free flow cross-sectional area of each of these sections is substantially constant throughout the length of the section and the free flow cross-sectional areas of adjacent sections are different. Moreover, the changes in cross-sectional area between adjacent sections are abrupt. Also, the length of each of the last three sections, that is, passage 27 and channels 45 and 55, is greater than the diameter of a circle having an area equal to the free flow area of the respective sections, in accordance with the principle diagrammatically shown in each of the sections illustrated in Fig. 1, while the diameter of a circle having an area equal to the area of the first section, namely channel 38, is not greater than twice the length of this section, as is permissible.

In operation, the rotation of the rotors 30 and 31 by means of a motor causes air to be drawn through hose 14 into dust bag 16. Here any entrained dust is deposited and the air passes through the material of the dust bag. This air passes through opening 35 to the center of rotor 30 and is discharged from the periphery of this rotor and passes through opening 33 to the center of rotor 31. The air discharged from the periphery of rotor 31 passes through air flow channel 38 and thence through air passages 27 in the motor. There is an abrupt change in cross-sectional area between air flow channel 38 and passages 27. From these passages the air passes through openings 46 into annular channel 45, there again being an abrupt change in the cross-sectional area. From channel 45 the air passes through filter 52 and into discharge channel 55, there being an abrupt change in cross-sectional area between channels 45 and 55. From here the air passes through outlet 48 to the atmosphere.

The sound produced by the rotation of the armature and the rotors 30 and 31, which would otherwise be carried out of the cleaner by the air stream, is to a great extent muffled by forc-

ing the air to suddenly expand and contract during its passage from the rotors to the outlet, as has been previously described. This results in a much quieter operation of the device.

While I have shown and described a preferred embodiment of my invention, it is to be understood that the scope thereof is to be limited only by the appended claims viewed in the light of the prior art.

What I claim is:

1. In a vacuum cleaner, a casing having an inlet opening and an outlet opening, a motor fan unit in said casing, the motor being between the fan and said outlet opening, and means providing an air flow channel between said fan and said motor, said channel having a substantially constant free flow cross-sectional area throughout its entire length, the cross-sectional area of said channel being equal to the area of a circle, the diameter of which is less than twice the length of said channel, said motor being formed with air passages therethrough in communication with said channel, the free flow cross-sectional area of said passages being substantially constant and different from that of said channel.

2. In a vacuum cleaner, a casing having an inlet opening and an outlet opening, a motor fan unit in said casing, the motor being between the fan and said outlet opening, said motor being formed with air passages therethrough having a substantially constant free flow cross-sectional area, the length of said passages being greater than the diameter of a circle having an area equal to the aggregate cross-sectional area of said passages, means for conveying air from said fan to the ends of said passages adjacent to said fan and a hood member between said motor and said outlet and forming with said casing an annular channel therebetween, said channel being in communication with the other ends of said passages, the cross-sectional area of said annular channel being substantially constant and different from that of said passages.

3. In a vacuum cleaner, a casing having an inlet opening and an outlet opening, a fan in said casing, a hood member between said fan and said outlet and forming with said casing an annular channel therebetween of substantially constant cross-sectional area, and a plate between said hood and said outlet forming with said casing a discharge channel having a substantially constant cross-sectional flow area which is different from the cross-sectional area of said annular channel.

4. In a vacuum cleaner, a casing having an inlet opening and an outlet opening, a motor-fan unit in said casing, the motor being between the fan and said outlet opening, means between said fan and said motor providing an air flow channel having a substantially constant free flow cross-sectional area, said motor being formed with air passages therethrough in communication with said channel, the free flow cross-sectional area of said passages being substantially constant and different from that of said channel, a hood member between said motor and said outlet and spaced inwardly from said casing to form an annular channel therebetween, said hood member being formed with openings for establishing communication between said passages and said annular channel, the cross-sectional area of said annular channel being substantially constant and different from that of said passages, and a plate between said hood and said outlet forming with said casing a discharge channel leading to said outlet.

- and having a substantially constant cross-sectional area being different from the cross-sectional area of said annular channel.
5. In a vacuum cleaner, a cylindrical casing having an inlet opening and an end formed with an outlet opening therein, the diameter of said casing being greater than that of said outlet opening, means for producing flow of air through said casing, and a circular plate within said casing adjacent to said outlet and forming with the end of said casing a discharge channel, the end of said casing being a hyperbolic surface whereby the cross-sectional flow area through said channel is substantially constant.
6. In a vacuum cleaner, a casing having an inlet opening and an outlet opening, a motor fan unit in said casing, the motor being between the fan and the outlet opening, and means providing a passageway for flow of air from said fan to said outlet opening, said passageway including a plurality of sections, each section being of substantially constant free flow cross-sectional area and adjacent sections being of different area with abrupt transitions therebetween, the cross-sectional area of each of said sections being equal to the area of a circle the diameter of which is less than twice the length of the respective section. 5 10
